(57) **CLAIM**

The ornamental design for a sterilization wrap material, as shown and described.

DESCRIPTION

FIG. 1 is a perspective view of a sterilization wrap material showing my new design;

FIG. 2 is a frontal view of the sterilization wrap material shown in FIG. 1;

FIG. 3 is a rear view of the sterilization wrap material shown in FIG. 1;

FIG. 4 is a bottom view of the sterilization wrap material shown in FIG. 2;

FIG. 5 is a top view of the sterilization wrap material shown in FIG. 2;

FIG. 6 is a side view as viewed from the right-hand side of the sterilization wrap material shown in FIG. 2; and,

FIG. 7 is a side view as viewed from the left-hand side of the sterilization wrap material shown in FIG. 2.

The broken lines shown in the drawings illustrate portions of the sterilization wrap material that forms no part of the claimed design.
